UNITED STATES PATENT OFFICE.

CHARLES DE QUETTEVILLE WHITTLE, OF KENILWORTH, ILLINOIS, ASSIGNOR TO ALFRED VESTER SONS, INC., OF PROVIDENCE, RHODE ISLAND, A CORPORATION OF RHODE ISLAND.

DESIGN FOR A CANOPY FOR LIGHTING FIXTURES.

Application filed January 26, 1926. Serial No. 16,275. Term of patent 7 years.

To all whom it may concern:

Be it known that I, CHARLES DE QUETTEVILLE WHITTLE, a citizen of the United States, residing at Kenilworth, in the county of Cook and State of Illinois, have invented a new, original, and ornamental Design for a Canopy for Lighting Fixtures, of which the following is a specification, reference being had to the accompanying drawing, forming part thereof, in which—

Fig. 1 is a side elevation showing my new design.

Fig. 2 is a partial plan view, only part of the ornamentation being shown, it being understood that the remainder is identical.

I claim—

The ornamental design for a canopy for lighting fixtures, as shown.

CHARLES DE QUETTEVILLE WHITTLE.
